UNITED STATES PATENT OFFICE.

ROGER A. SELBY, OF PORTSMOUTH, OHIO.

DESIGN FOR A SHOE.

Application filed February 27, 1929. Serial No. 30,237. Term of patent 3½ years.

To all whom it may concern:

Be it known that I, ROGER A. SELBY, a citizen of the United States, residing at Portsmouth, in the county Scioto and State of Ohio, have invented a new, original, and ornamental Design for Shoes, of which the following is a specification, reference being had to the accompanying drawing, forming part thereof.

The drawings show my design as applied to shoes and particularly ladies' shoes.

shoe, showing my new design; and

Figure 2 is a view of the outer side of the shoe shown in Figure 1.

I claim:

The ornamental design for a shoe, as shown.

ROGER A. SELBY.
